CLAIM

I claim the ornamental design for a bottle, substantially as shown and described.

DESCRIPTION

FIG. 1 is a top front isometric view of a first embodiment of a bottle.

FIG. 2 is a bottom front isometric view of the bottle of FIG. 1.

FIG. 3 is a front elevation view of the bottle of FIG. 1.

FIG. 4 is a rear elevation view of the bottle of FIG. 1.

FIG. 5 is a right side elevation view of the bottle of FIG. 1.

FIG. 6 is a left side elevation view of the bottle of FIG. 1.

FIG. 7 is a top plan view of the bottle of FIG. 1.

FIG. 8 is a bottom plan view of the bottle of FIG. 1.

FIG. 9 is a top front isometric view of a second embodiment of the bottle.

FIG. 10 is a bottom front isometric view of the bottle of FIG. 9.

FIG. 11 is a front elevation view of the bottle of FIG. 9.

FIG. 12 is a rear elevation view of the bottle of FIG. 9.

FIG. 13 is a right side elevation view of the bottle of FIG. 9.

FIG. 14 is a left side elevation view of the bottle of FIG. 9.

FIG. 15 is a top plan view of the bottle of FIG. 9; and,

FIG. 16 is a bottom plan view of the bottle of FIG. 9.

The broken lines, which define the bounds of the claimed design, form no part of the claimed design.

1 Claim, 8 Drawing Sheets
